SEED SORTING MACHINE

Lee A. Medcalf, Fairgrove, Mich.

Application November 1, 1940, Serial No. 363,817

9 Claims. (Cl. 209—113)

This invention relates to seed sorting machines such as used for picking beans and separating the perfect product from the imperfect product.

One of the prime objects of the invention is to design a sorting machine by means of which pods, foreign matter, splits, and imperfect beans can be separated from the perfect beans.

Another object is to design a sorting machine including driven sorting rolls onto which the beans are fed, and provide means cooperating with said rolls whereby splits, cracked beans, and other foreign matter will be carried outwardly over the rolls, and the perfect product forced inwardly and into the trough formed between each pair of rolls.

A further object is to provide a feed box including means for agitating and distributing the beans over the entire length of the sorting rolls as the machine is operating.

A still further object is to provide an adjustable screen frame assembly including means for reciprocating said screen frame.

With the above and other objects in view, the present invention consists in the combination and arrangement of parts hereinafter more fully described, illustrated in the accompanying drawings, and more particularly pointed out in the appended claims, it being understood that changes may be made in the size, proportions, and minor details of construction without departing from the spirit, or sacrificing any of the advantages of the invention.

In the drawings:

Fig. 1 is a side elevational view of my improved seed sorting machine, showing it mounted on a chassis for easy portability,

Fig. 2 is a top plan view,

Fig. 3 is an enlarged, fragmentary, transverse sectional view, showing one pair of sorting rolls, and roll feeding means, the arrows indicating the direction of rotation of the sorting rolls,

Fig. 4 is a fragmentary, side elevational view of the feed box and feed means,

Fig. 5 is a detail end view assembly of the feed box and drive,

Fig. 6 is a fragmentary, isometric view showing the feed box and the means for adjusting the discharge openings therein, and,

Fig. 7 is an enlarged fragmentary plan view showing one of the sorting rollers and a deflector, etc.

Fig. 8 is an enlarged fragmentary side view showing the screen frame reciprocating means.

Referring now more particularly to the drawings, in which I have shown the machine set up

to sort beans, the numeral 8 indicates a structural frame of conventional design mounted on a vehicle frame 9 carried on ground engaging wheels 10 and springs 11 are connected to the axle 12 and vehicle frame 9 in the usual manner so that the machine is readily portable, and so that it can be blocked and the pitch of the sorting rolls adjusted as desired.

Sorting rolls 13 and 14 respectively, are mounted on shafts 15 as usual, which shafts are journaled in suitable bearings (not shown) provided in the end members of the frame, and intermeshing gears 16 are provided on the ends of said shafts, a bevel gear 17 being provided on one of the shafts 15, said gear meshing with and being driven by a pinion 18 provided on the drive shaft 19. This shaft 19 is journaled in brackets 20 projecting from the end of the machine frame, and a drive pulley 21 is mounted thereon.

A motor 22 is mounted on a suitable bracket support 23 suspended from the frame 8 and a belt 24 serves to drivingly connect the pulleys 21 and 25 in the conventional manner, the motor being connected to any suitable source of power.

A seed hopper 26 is mounted on the machine frame by means of supports 27, and a gate 28 is provided in the spout of said hopper for regulating the discharge of seed therefrom.

A screen frame 29 is disposed beneath the feed hopper 26 and screens 30 and 31 respectively, are mounted therein, the screen 30 being of relatively large mesh and is designed to screen out pods and other foreign matter, while the screen 31 screens out dirt, small beans, and splits, etc., which fall onto an imperforate bottom plate 32, and are thence discharged to a suitable bin (not shown) through the trough 33, the product passing over the screen 31 discharging from the end of said screen and into the longitudinally disposed, distributing box 34 which forms a part of the main frame.

The screen frame 29 is mounted on spaced supports 35, which supports are pivotally connected to the machine frame and screen frame respectively, at the point 36. A shaker mechanism B is connected to said frame, and is actuated from the cam 37, a groove 38 being provided in the periphery of said cam, and one end of a follower 39 is mounted in said groove, said follower being mounted on a bracket 40 being revolvably mounted on the shaft 41, the opposite end of said follower being pivotally connected to a link 42 which is in turn pivotally connected to the supports 35, so that as the cam is driven, the screen frame will be actuated accordingly.

A feed box 34 is disposed directly over each pair of rolls 13 and 14, and spaced apart openings 43 are provided in the bottom wall 44. Angles 45 are secured to the respective side walls of the box 34 and an adjustable gate 46 is slidably mounted on said angles in facial contact with the plate 44, said plate being slidable to adjust the size of the openings 43 as desired.

A second imperforate distributing plate 47 is disposed a predetermined distance below the feed box 34 and is slightly crowned as shown, and as the beans discharge through the openings 43 onto this plate 47, they will roll outwardly and off the edges of the plate, falling onto the rolls 13 and 14 as clearly shown in Fig. 3 of the drawings.

Positive agitating and conveying means are provided in the feed box 34 and comprises a shaft 48 mounted in suitable bearings 49 provided on the box, and having agitators 50 mounted thereon directly over each discharge opening, a helical wire conveyer 51 being provided on the shaft for agitating and conveying the beans to said discharge openings. The gate 46 controls the area of the discharge openings 43 and is manually adjustable in the usual manner. The shaft 48 projects from the upper end of the feed box 34, and a sprocket 52 is mounted thereon, a chain 53 serving to drivingly connect said sprocket with sprocket 54 provided on the shaft 15.

A sectional roller C is mounted in hanger brackets 56 hung from the frame, this roller comprising a plurality of relatively thin disks 57 having an enlarged, centrally disposed opening 58 through which the shaft 59 extends, said shaft being mounted in the brackets 56 and is free to move vertically if necessary and desirable, and it is also quickly removable inasmuch as the brackets 56 are open.

A second longitudinally disposed roller 60 is disposed directly adjacent the sectional roller C and serves to force the disk sections back to proper position as the sorting rolls carry the splits around. These splits due to their shape and texture are carried over by the sorting roll, raising the disks which come in contact therewith, and some of these disks might, due to frictional contact, be sluggish in returning to original position if such rollers were not provided.

Gaps appear in the sectional rollers C where the hanger brackets 56 engage the shaft 59 (see Fig. 7 of the drawings), and to prevent the good product passing therethrough with the splits, I provide a resilient deflector 61, formed as clearly shown in Fig. 7 of the drawings; this is mounted on a hanger bar 62 and closes the gap. Openings 63 are provided in the edge of the distributor plate 47 and as the perfect product cannot pass beneath the section roll C, it travels along the face of the sorting roll, in the direction of pitch and through one of the openings 63, the metal being bowed as at 65 to form a lip which together with the deflector 61, deflects the perfect product through the openings 63 and into the trough formed between the sorting rolls, thence discharging into the trough 66 in the usual manner.

The rolls 13 and 14 rotate in opposite directions, and as the beans are discharged from the feed box 34 onto the sorting rolls 13 and 14, the splits, cracked, and imperfect beans are carried over and between the sorting roll and sectional roll C, while the round perfect product gradually travels down with the pitch of the rolls, until they are deflected inwardly through the opening 63 by the deflectors 61, thence being discharged

into a trough 66 from where they are bagged or discharged into a suitable bin or receptacle (not shown).

The splits, cracked beans, and imperfect product are carried over and discharged in the direction of rotation of the rolls, and suitable troughs (not shown), can be provided for catching this discharging product.

In practice the product to be picked is placed in the hopper 26 from which it flows onto the screen 30 which is actuated from the cam 37, the pods and foreign matter discharging into the trough 33, while the beans pass over the screen 31 and thence discharge into the feed box 34, the sand, chaff, etc., falling onto the imperforate plate 32 and being discharged into another trough (not shown).

The helical conveyers 51 are driven from the sprockets 52 and carry the beans to the discharge openings 43, thence the beans discharge onto the bottom plate 47, thence discharging over the edges and onto the face of the rolls 13 and 14, the splits, culls, and imperfect product traveling outwardly between the sorting rolls and the sectional rolls, while the perfect product rolls into the trough between the sorting rolls, finally discharging into the trough 66 provided at the lower end of the machine. The pitch of the sorting rolls can be adjusted in any desired manner, and the area of the openings in the feed box can be easily controlled by means of the gates 46.

From the foregoing description, it will be clearly obvious that I have perfected a very simple, practical, and economical sorting machine for sorting beans and similar products.

What I claim is:

1. A sorting machine of the class described comprising a frame, an inclined feed box mounted thereon and into which the product is fed, discharge openings in said box, a distributing plate below said box, sorting rolls having frictional surfaces disposed parallel with said feed box below said plate and onto which the discharged product is discharged, a shaft parallel with said sorting rolls, and a plurality of disk-shaped members loosely mounted on said shaft and riding on said sorting roll.

2. A sorting machine of the class described comprising a frame, sorting rolls having frictional surfaces journaled thereon, a shaft parallel with the rolls, a plurality of thin disks loosely mounted thereon for movement in a vertical direction with relation to said shaft and riding on said sorting roll, and means for feeding the product onto said rolls.

3. A sorting machine of the class described comprising a mobile frame, driven sorting rolls having frictional surfaces journaled thereon, shafts adjacent said rolls, and a plurality of thin disks loosely mounted thereon and riding on said rolls, and a second driven roll journaled on said frame adjacent said disks and in engagement therewith.

4. A sorting machine of the class described comprising a frame, driven sorting rolls having frictional surfaces journaled thereon, a removable shaft parallel with and adjacent each roll and provided with a plurality of thin disks mounted thereon and riding on said roll, a discharge plate, a feed box above said plate and parallel with the rolls and provided with discharge openings open to said plate, means for conveying the product in the box for discharging onto said plate, agitating means disposed over

each discharge opening, and means driving said agitating and conveying means.

5. A sorting machine of the class described comprising a frame, driven sorting rolls having frictional surfaces journaled thereon, a feed box disposed in parallel relation above said rolls and provided with adjustable discharge openings therein, a distributing plate below said box and deflecting the product onto said rolls, a shaft over each sorting roll, and a plurality of thin disks loosely mounted thereon and riding thereon, said disks being movable vertically with relation to each other, driven agitating means disposed over each discharge opening, and conveying means in said feed box for conveying the product to said discharge opening.

6. A sorting machine of the class described comprising a frame, longitudinally disposed sorting rolls having frictional surfaces journaled thereon, a feed box into which the product to be sorted is fed, manually controlled discharge openings in said box, a distributor plate interposed between said box and rolls for deflecting the product onto said rolls, a shaft loosely mounted on the frame, a plurality of thin disks loosely mounted thereon and riding on said rolls at a point directly adjacent the point at which the product discharges onto the rolls, and a driven roller journaled on said frame and engaging said disks.

7. A bean sorting machine comprising a frame, longitudinally disposed sorting rolls having frictional surfaces journaled thereon, a feed box adapted to receive the product to be sorted, discharge openings therein, a deflector plate inter-

posed between said box and sorting rolls for directing the product onto said rolls, spaced apart openings in the edge of said plate, a shaft mounted on the frame, a plurality of relatively thin disks mounted for vertical movement on said shaft and riding on the roll, means for deflecting the good product back through deflector plate openings, and conveying means in the feed box for distributing the product in said box.

10 8. A bean sorting machine including a frame, a driven frictional sorting roll journaled thereon, a sectional roll comprising a shaft having a plurality of thin disk members mounted thereon and riding on said roll, said disks being movable vertically with relation to each other, hanger brackets mounted on said frame and supporting said shaft at points intermediate its length, resilient clips disposed adjacent said brackets for deflecting the product being sorted inwardly and away from the direction of rotation of said roll, and means for feeding and distributing the product to be sorted onto said roll.

15 9. A bean sorting machine including a frame, a driven frictional sorting roll journaled thereon, a sectional roll adjacent to and riding on said sorting roll and comprising a plurality of thin disks vertically movable on said shaft, a deflector plate for directing the product to be sorted onto said sorting roll, spaced apart openings in the edge of said deflector plate, and a deflector adjacent each opening for deflecting the product inwardly and away from the direction of rotation of said sorting roll.
